SERVICE SIGNAL LAMP FOR RESTAURANT
TABLES AND THE LIKE

Loren G. Custer, 1850 Capital St. SE., Salem, Oreg.

Filed Nov. 12, 1963, Ser. No. 77,384

Term of patent 14 years

(Cl. D72—1)

FIGURE 1 is a side elevational view of a service signal lamp for restaurant tables and the like embodying my new design; and

I claim:

The ornamental design for a service signal lamp for restaurant tables and the like, as shown.
